DESIGN FOR A RAG DOLL

Léda Hincks Plauché, New Orleans, La.

Application May 28, 1935, Serial No. 57,058

Term of patent 3½ years

To all whom it may concern:

Be it known that I, Léda Hincks Plauché, a citizen of the United States, residing at New Orleans, in the Parish of Orleans and State of Louisiana, have invented a new, original, and ornamental Design for Rag Dolls, of which the following is a specification, reference being had to the accompanying drawing, forming part thereof.

I claim:

The ornamental design for a rag doll, as shown.

LÉDA HINCKS PLAUCHÉ.
